(57) **CLAIM**

The ornamental design for packaging for sensing accessory, as shown and described.

DESCRIPTION

FIG. 1 is a front view of packaging for sensing accessory embodying our new design shown in an open position; FIG. 2 is a rear view thereof shown in an open position; FIG. 3 is a bottom view thereof shown in an open position; FIG. 4 is a top view thereof shown in an open position; FIG. 5 is a side view thereof as seen from the right-hand side of FIG. 1;

FIG. 6 is a side view thereof as seen from the left-hand side of FIG. 1;

FIG. 7 is a bottom perspective view thereof shown in an open position;

FIG. 8 is a top perspective view thereof shown in an open position; and,

FIG. 9 is a front view thereof shown in an open position with a closed tab and a sensor and patches positioned in the packaging, the sensor, patches, and portion of the tab not forming any part of our claimed design.

The broken lines shown represent unclaimed subject matter and form no part of the claimed design.

1 Claim, 7 Drawing Sheets
